UNITED STATES PATENT OFFICE.

PATRICK B. DELANY, OF SOUTH ORANGE, NEW JERSEY, ASSIGNOR TO THE TELEPOST COMPANY, OF NEW YORK, N. Y., A CORPORATION OF MAINE.

TELEGRAPHY.

1,161,929.

Specification of Letters Patent. Patented Nov. 30, 1915.

Application filed September 9, 1910. Serial No. 581,216.

To all whom it may concern:

Be it known that I, PATRICK B. DELANY, a citizen of the United States, residing at South Orange, county of Essex, State of New Jersey, have invented a new and useful Improvement in Telegraphy, of which the following is a specification.

This invention relates primarily to that automatic telegraph system in which transmission of signals is effected by means of a perforated tape and a record of transmitted signals made by electro-chemical action upon a tape.

The object of the invention is to improve the working of such lines by obviating the evil effects of electrostatic capacity and self-inductance or an unbalanced proportion of these two conditions; and also to protect the line against the evil inductive effects due to the proximity of conductors carrying high power currents.

To this end, the invention comprises an organization in which each signal, such as a dot or dash, is initiated by a current of one polarity and terminated by a current of the other polarity and wherein the line is at all times occupied by a current of either the one or the other polarity. A line under the latter condition is one that may be termed locked or closed against disturbing inductive effects from adjacent high current conductors.

Combined with the arrangement thus far described is a means whereby there is a gradual rise of potential at the beginning of each signal impulse, whether positive or negative, and a drop in potential at the end of each impulse.

In the accompanying drawing, which shows an organization that experience has demonstrated to be a practical and efficient embodiment of the invention, Figure 1 is a diagrammatic view showing a sending and receiving station connected by a main line; Fig. 2, a diagrammatic view showing a modification of the arrangement at the sending station; Fig. 3 shows a section of transmitting tape with perforations for transmitting the word "Washington"; and Figs. 4, 5, 6, 7, 8 and 9 show sections of receiving tape with records thereon.

Referring to Fig. 1, 1 represents the tape drawing rolls of a transmitting apparatus.

2 indicates the perforated transmitting tape having two rows of perforations. 55 Pairs of perforations in lines perpendicular to the tape represent dots and those in lines oblique represent dashes.

3 and 4 are upper and lower transmitting fingers opposed to each other and coming in contact through the lower series (as viewed in the drawing) of the perforations; and 5 and 6 represent another pair of the opposed transmitting fingers coming in contact through the perforations in the upper row. 65 The lower finger 4 is connected with the positive pole of the transmitting battery B and the other lower finger 6 is connected with the negative pole. The two upper fingers 3, 5, are electrically united and connected with the main line L and also through a conductor 7 and adjustable resistance 8 through the coils of a polarized relay R to earth. The stops 9 and 10 of the relay armature member are connected respectively with the negative and positive poles of battery B; and the armature member is connected through an adjustable resistance 11 with the main line L. 70 75

At the receiving station 12 is the recording finger connected to the main line, and 13 its companion finger connected to earth.

14 indicates the ordinary chemically treated recording tape.

Since in the particular character of transmitting tape indicated the pairs of perforations representing dots are in lines perpendicular to the tape, the opposed pair of contact fingers 5, 6, are placed a suitable distance in advance of the other pair of 85 contact fingers, 3, 4. The signal initiating impulses are from the positive pole of the transmitting battery through the contact fingers 3, 4 to line, and the signal terminating impulses are from the negative pole of 90 the transmitting battery to line through contacts 5, 6.

In Fig. 1, the armature lever of relay R is against its stop 9, and the negative pole of battery B is connected to line through resistance 11. This is a condition that always exists at the time a signal impulse is to be 100

sent. When the contact fingers 3, 4 meet through the perforation, the positive pole of the battery is connected through the fingers to line and is not of full strength, being opposed by the other pole of the battery connected at the moment to the line through resistance 11. Current from the positive pole of the battery now simultaneously passes through the coils of polarized relay R.

10 The first effect is, for a very brief instant, to impair the contact of the armature lever of the relay with its stop 9, thereby further reducing the opposition of the negative pole of the battery, and when the armature lever

15 relay R leaves its stop 9, the strength of the impulse on the line from the positive pole of the battery rises to a maximum. When the contact fingers 3, 4 are separated by the body of the transmitting tape, the

20 positive pole of the battery is still connected to line through the resistance 11, the armature lever of the relay being then against its stop 10. When, however, the transmitting tape is advanced sufficiently, contact

25 fingers 5, 6 come together through the companion dot perforation in the upper series and the negative pole of the transmitting battery is connected to line through them and also to earth through the coils of the

30 relay. The strength of the impulse from the negative pole of the battery at the beginning is opposed by the positive pole of the battery connected to line through the resistance 11, and when the relay armature

35 passes again to its stop 9, the strength of the negative impulse on the line is at a maximum.

Fig. 2 indicates a modification in which the coils of the relay are in series with the 40 transmitting fingers and main line. The operation is the same generally as already described. The organization shown in Fig. 1 is, however, preferred.

Fig. 4 is a representation of a receiving 45 tape having the word "Washington" in dots and dashes thereon. The dots and dashes have been made in the ordinary way without supplementing the current on the line after the contact fingers 3, 4 are separated.

50 As the dots and dashes are represented by the space or interval of time between the positive and negative impulses transmitted through the perforations in the transmitting tape, the extension marking representing the

55 dashes is due to the static charge in the line or, as it is usually called, "tailing."

Fig. 5 shows a receiving tape with the same record, produced, however, by supplementing the initial marking impulse by the 60 full strength of the current and maintaining the full strength upon the line until the reversal occurs.

Fig. 6 shows a transmitting tape with the same record made where the supplementary

current, or that maintained upon the line until the reversal occurs, is weaker.

Fig. 7 shows a succession of dots made without supplementation of the marking current.

Fig. 8 shows a like succession of dots made when the marking current has been supplemented and maintained upon the line.

Fig. 9 shows a receiving tape having upon it in dots and dashes "this is the way" produced by the use of two recording fingers over a line locked as described against outside effects by maintenance of current on the line at all times.

In the system above described, there is a practically closed or locked circuit in which a current is always maintained, and a gradual rise of potential at the beginning of each impulse and a drop at the end. Static discharge affecting the record is prevented by a continuance of the signal impulse weakened to such a degree as to be sufficient not only for that purpose but for a reinforcement of the maximum potential of the impulse to permit of the record being continued to the next reversal.

As to induced currents from adjacent wires, with a non-marking ground connection at the receiver, those of a negative character would not show on the tape in any event while those of positive polarity would coincide with the signal being recorded at the time; and inductive impulses of positive polarity occurring during the time that the negative battery current occupies the line (representing spaces between the elements 1 of a letter or spaces between letters and words) would be neutralized by the negative battery current maintained on the line. It will be seen that the weakened or attenuated battery currents are superseded at each 1 reversal by the stronger impulses and that at no time is the line disconnected from a source of current. The reversal through a perforation is not met by a current of equal strength at the relay contact but by a much 1 weaker one that is overcome without an appreciable period of neutrality: nor is the armature of the relay moved from its contact until the reversal has had time to establish itself on the line simultaneously with 1 magnetization of the relay. Doubtless also the change from the weak current to the stronger reversal is not abrupt but is, on the contrary, gradual owing to the impedance of the relay coils and the change of 1 pressure between the armature and its contact so that at a speed of, say, about three hundred words a minute, the relay armature will have reached the opposite contact before the contact between the transmitting

1 fingers is broken by the edge of the perforation in the tape. The self-induction impulse from the polarized relay winding following

each signal is lost in the reduced current, or, it may be neutralized by a condenser in shunt around the relay in the ordinary way. Sparking at the transmitting contact fingers is prevented by the supplementary contacts at the relay and will not occur at the relay contacts because of the weak current.

Since the dashes are formed by the supplementary impulses sent into the line from 10 the relay contacts, and as these are comparatively weak, the static discharge from the line becomes almost negligible and will not be sufficient to appreciably interfere with the next succeeding impulse.

15 I claim:

1. In telegraphy a method of transmission comprising maintaining a closed main circuit, impressing at all times thereon current of either positive or negative polarity 20 and forming signal impulses by impressing on such circuit successively two fixed strengths of current of the same polarity, the signal producing currents being of uniform duration and regularly alternating in 25 polarity.

2. In telegraphy the method of transmission comprising maintaining a closed main circuit, impressing thereon at all times current of either positive or negative polarity 30 and beginning a signal impulse with a current weakened by an opposing current, continuing said signal impulse by the same current unopposed and ending said signal with the same current weakened by introduction 35 of resistance.

3. In telegraphy the combination of a circuit, a transmitter in said circuit, a transmitter in a parallel circuit with and controlled by said first transmitter, and circuit 40 connections whereby each of said transmitters sends a portion of each signal into the circuit.

4. In telegraphy the combination of a

telegraph circuit, a perforated tape representing signals, letters and spaces, an automatic transmitter sending said signals into said circuit, an electromagnet controlled by said automatic transmitter and means controlled by said electromagnet for prolonging the impulses sent into the circuit by 50 said automatic transmitter and for maintaining a current in said circuit during the time represented by spaces between impulses, letters and words.

5. In telegraphy the combination of a perforated tape representing signals, an automatic transmitter for sending signals represented on the tape into a circuit, a polarized relay actuated by said automatic transmitter for also sending impulses into the circuit which latter impulses prolong the impulses sent into the circuit by the automatic transmitter.

6. In telegraphy the method of forming a signal consisting of beginning said signal 65 with a current partially weakened by a current of opposite polarity, discontinuing said current of opposite polarity and continuing said signal by the same current of full strength, reducing said current and ending 70 said signal by reduction of said reduced current by an opposing and reversing current.

7. The combination of a perforated tape transmitter by which currents of equal duration and alternating polarity are transmitted and means whereby a current initiating a signal is maintained upon the line during the interval between it and the succeeding current of opposite polarity.

In testimony whereof, I have hereunto subscribed my name.

PATRICK B. DELANY.
